DESIGN.

—o—
J. L. FOLSOM.

CARPET.

No. 17,480.

Patented July 26, 1887.

UNITED STATES PATENT OFFICE.

JAMES L. FOLSOM, OF BROOKLYN, NEW YORK, ASSIGNOR TO THE HARTFORD CARPET COMPANY, OF HARTFORD, CONNECTICUT.

DESIGN FOR A CARPET.

SPECIFICATION forming part of Design No. 17,480, dated July 26, 1887.

Application filed June 15, 1887. Serial No. 241,419. Term of patent 3½ years.

To all whom it may concern:

Be it known that I, JAMES L. FOLSOM, of Brooklyn, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face view 15 of a carpet showing my new design.

My design consists of a number of figures irregularly disposed upon the surface of the carpet upon any suitable ground.

Figure A is composed of a central circular 20 flower form encircled by a number of leaves forming a spiral-shaped group. Little sprays and small flowers are scattered around the edges of the figure.

Figure B (shown at the left side and the

upper and lower right-hand corners of the 25 photograph) is a cluster of leaf figures, and is bowl shaped at the lower part, with one or two curving leaves projecting up from the center of the bowl form and a number of leaves massed at the center.

Figure C is a group of leaves irregularly intertwined, having a general curving outline, with large lobed leaf figures projecting from either side.

Figure D is a leaf cluster, having a number 35 of convoluted leaves forming the larger portion of its mass, and several lobed leaf figures partially encircling the former, with a prominent leaf figure projecting at one side.

What I claim as new, and desire to secure 40 by Letters Patent, is—

The design for carpets, consisting of the design substantially as shown.

JAS. L. FOLSOM.
